UNITED STATES PATENT OFFICE.

THOMAS L. PERRIN, OF BROOKLYN, NEW YORK.

STERILIZING APPARATUS FOR SURGICAL INSTRUMENTS.

1,107,834.

Specification of Letters Patent. Patented Aug. 18, 1914.

Application filed March 11, 1913. Serial No. 753,586.

To all whom it may concern:

Be it known that I, THOMAS L. PERRIN, a citizen of the United States, residing at 352 Clinton street, Brooklyn, in the county of Kings and State of New York, have invented a new and useful Improvement in Sterilizing Apparatus for Surgical Instruments, of which the following is a specification.

This invention relates to sterilizing apparatus for surgical instruments, particularly dental instruments which must be used repeatedly upon various patients.

In the course of the usual practice of the dentist during which he is required to work upon a large number of patients, the problem arises how to sterilize the instruments so as to secure the patients from infection. It is necessary that some quick and certain apparatus be had so that no time need be wasted on the part of the dentist and at the same time secure a thorough sterilization.

The principal object of my invention is to fulfil the above requirements and to this end I have provided an apparatus consisting of two telescoping shells, the interior one of which is in the form of a receptacle in which a suitable powdered medium, such as fine sand or powdered asbestos may be placed. The heat is applied to the bottom of the interior shell and allowed to travel up through the space between it and the surrounding outer shell, thus securing a maximum heating surface calculated to heat up the powdered medium rapidly and with the least possible waste of heat. Within the inner shell or receptacle are disposed racks in which smaller instruments, such as burs, drills, etc., may be readily placed, while in the main portion of the receptacle the larger appliances, such as carborundum wheels, disks, forceps, or even bottles may be thrust for sterilization.

In the drawing illustrating my invention Figure 1 is a sectional elevation of an apparatus embodying my invention, the section being taken along line *a—a* of Fig. 2. Fig. 2 is a plan view with the cover removed.

Referring in detail to the drawing, the apparatus consists of an outer shell 10 having in the interior thereof spaced ribs 11 abutting the interior shell or receptacle 12. Within this receptacle may be placed a suitable powdered heat absorbing medium 13, such as powdered sand or asbestos. In this medium may be thrust any instrument or appliance desired to be sterilized. In Fig. 1 I

have illustrated a bottle 14 which is inserted in the powdered substance.

For the smaller tools, such as burs, drills, etc., I provide at the interior of the receptacle 12 and attached to the wall adjacent to the top thereof, pans 15 and 16 of varying depths. These pans are covered with the perforated covers 17 and 18 having overturned hooked portions 19 and 20 which engage the interior walls of these pans. These perforated covers form racks into which the small slender tools 200 may be readily inserted and thrust into the powdered medium contained in the pans, and thus assurance is had that these small tools are not lost. In fact these racks may serve as convenient holders for the tools, in which holders the latter may readily be found always in a sterilized condition.

A partition wall 21 may be formed to divide the receptacle into two main compartments into which different instruments or appliances may be inserted.

The bottom of the outer shell 10 is preferably formed with perforations 22 to admit air for the flame, so as to aid combustion, and the space between the outer shell and the receptacle affords a flue for the heated gases, thus providing a large heating surface for rapidly heating up the receptacle. The heated gases in passing through this flue contact the portion of the wall immediately about the pans 15 and 16 and thus cause the contents of the latter to heat up more rapidly.

A suitable cover 23 may be applied to the mouth of the receptacle to retain the heat therein and also to give a finished appearance to the device.

By regulating the burner, the heat retaining substance in the receptacle may be maintained at the desired temperature, which is about from 220 to 230 degrees, a temperature sufficient to kill all germs, but insufficient to affect the temper of the instruments.

Having thus described my invention, I claim as new and desire to secure by Letters Patent—

1. An apparatus for sterilizing dental instruments, comprising an outer shell, a receptacle within the shell and spaced therefrom, comparatively shallow pans within the receptacle, perforated covers for the pans, and a powdered heat retaining substance within the receptacle and pans, into which

the large instruments and the small slender instruments may respectively be inserted.

2. An apparatus for sterilizing dental instruments, comprising a receptacle, a shallow pan within the receptacle attached to the upstanding wall thereof, a removable perforated cover for the pan having a portion thereof engaging the wall of the pan and a powdered heat retaining substance within the receptacle and pan into which instruments of various sizes may be inserted and held for sterilization.

3. A sterilizing apparatus for dental instruments, comprising an outer shell having a plurality of perforations adjacent the bottom thereof, an inner receptacle held in spaced relation to the shell, a pan held within the receptacle adjacent the top thereof into which the smaller instruments may be inserted, the heat from the heater at the bottom of the receptacle traveling up through the space between the receptacle and the shell and past the pan, and a powdered heat retaining space within the receptacle and pan.

4. A sterilizing apparatus for dental instruments, comprising an outer shell, an inner receptacle held in spaced relation to the shell, small pans adjacent to the top of the receptacle, a partition dividing the body of

the receptacle into two compartments and a heat retaining powdered substance within the compartments and pans into which the various tools may be inserted and held for sterilization.

5. A sterilizing apparatus for dental instruments, comprising an outer shell, an inner receptacle held in spaced relation to the shell, small pans of varying depths adjacent to the top of the receptacle, racks over said pans into which small instruments may be inserted, a partition dividing the body of the receptacle into two compartments and a heat retaining powdered substance within the compartments and pans into which the various tools may be inserted and held for sterilization.

6. An apparatus for sterilizing dental instruments, comprising a receptacle, a shallow pan within the receptacle and attached thereto, a powdered heat retaining substance within the receptacle and pan into which instruments of various sizes may be inserted and held for sterilization, and a rack over the pan in which small instruments may be held.

THOMAS L. PERRIN.
